INSTALLATION FOR COMPILING AND COL-
LABORATING STATISTICAL DATA

Charles Borel, Geneva, Switzerland

Application December 11, 1928, Serial No. 325,341
In Switzerland December 14, 1927

7 Claims. (Cl. 164—115)

The present invention relates to the so-called "continuous strip" statistical apparatus, and is designed to replace the somewhat inadequate type of apparatus using perforated cards. It allows the recording of data of transactions regarding one specific item chronologically and interspersed between other data, and to coordinate such data referring to this item subsequently and in any manner desired. It allows the extension of the recording of data relating to a specific item beyond the space of an individual field of the continuous record strip, and to obtain subsequently the cooperation of the different strip fields in any manner desired. It provides for the combined, simultaneous and reciprocal operation of any group of data sources identified by the same characteristic and recorded consecutively or in any other order. It allows the suspension of the cooperation of different fields in a given data group by changing, delaying or completely suspending the movement of the record strip or by changing the sequence of perforated fields of a record strip automatically in accordance with determined data or requirements of the particular case. It provides for the repeated forward and backward movement of the record strip through the apparatus to obtain complete reproduction of the perforated data fields in predetermined sequence.

Applicant's invention, which employs some of the apparatus disclosed in his prior Patent 1,863,097, granted June 14, 1932, eliminates on the basis of the above mentioned innovations many shortcomings of the present apparatus using perforated cards.

The record strip is subdivided into individual fields of equivalent widths each containing a predetermined number of lines for the recording of indices and data.

As is usual in the automatic preparation, all the values are indicated by numerals, each numeral of which may be represented by a perforation on the corresponding line of the perforation document, either by the perforation of a single point, of a line provided for ten or twelve points, or by the combined perforation of a single or of a plurality of points in a line providing for four points. Both kinds of perforation may be employed. The latter, code-like form of perforation, however, permits representing 16 different data or statements in each line of four points, in addition to the representation of a datum by no perforation at all, and consequently permits the material limitation of the size of the field of the card. It is for this latter reason

that in the example to be described and illustrated recourse is had to the method providing for lines of four points.

In the case that not only values but also signs or letters are to be transferred on the writing or recording sheet of the printing apparatus, which apparatus may be for instance of the type shown in my prior Patent 1,863,098, granted June 14, 1932, the code lines are provided with five instead of four points, the perforating combination of which five points will permit 32 different signs.

In the drawings, Fig. 1 diagrammatically illustrates a portion of the installation for automatically recording data in predetermined order from a strip on which data is recorded at random and this figure discloses among others, quite schematically, a reading mechanism of the type disclosed in my Patent 1,863,097, granted June 14, 1932.

Fig. 2 discloses the remaining part of this apparatus for reproducing data in predetermined order, the part termed distributor.

Fig. 3 is a fragmentary showing of a strip such as is produced according to my invention, the said strip being divided into a plurality of fields, in each field of which a plurality of data is shown as recorded in code.

Figs. 4-7 show the various types of control and record strips which are produced during the several phases of regrouping according to my apparatus, while at the right of Figs. 5-7, the various relay connections are schematically indicated.

Fig. 8 diagrammatically illustrates a "com- 35
parer".

In the study of the given examples, it is to be kept in mind that the first line of all the fields of a group serves for receiving the particular indices, which automatically release certain operations, and in particular the motion of the perforated strip. The second and the next to last group fields of each strip receive exclusively the perforation of the index 1 (i_1 in Fig. 3), while in the first and the last group fields the index 2 (i_2 in Fig. 3) is punched in advance. The index 3 (perforation indicated by i_3 in Fig. 3), of the first line of a group field (corresponding to the space reserved for four perforations and, shown between the heavier black lines in Fig. 3), designates either the end or the beginning of a separated field series (as schematically indicated by brackets designated as $n_3=0$, $n_3=2$, etc. on Fig. 5). The perforation of the index 4 (i_4 in Fig. 3) nullifies the corresponding group field 55

and prevents the use of its data. The contacts 2 and 4 of line 5 of the reader 1 (Fig. 1) were not connected to prevent unnecessary complication of the drawing and because they are not required in the particular application of the invention explained in this specification. The same consideration applies to the relays 2 and 4 of 39 (Fig. 1).

With the aid of a group of relays switched in the circuits of an installation, the appearance of the index 2 in the perforated strip under the reader will automatically cause the interruption of current to all the cooperating apparatus. If the index 4 appears, all transfers and operations will cease with the sole exception of the substitution of the cancelled group field by the next following. Together with the required switches this group of relays also serves for the starting and the stopping of the apparatus.

As aforesaid, the rational and most speedy cooperation of two or more perforated strips eventually calls for the prior rearranging in predetermined order of their group fields, which are indicated by any one of the common data such as number of the class, etc. The Figs. 1 to 7 illustrate the apparatus and procedure employed in regrouping a strip P6 in accordance with its data: n3 (hundreds), n2 (tens) and n1 (units). The installation (Figs. 1 and 2) comprises, apart from some individual relays and switches which will be treated later on, the following devices:

1. It comprises a current dispatcher (Fig. 2) of conventional design consisting of a number of cams rotating on the driving shaft of the installation, which cams close switches and thereby close the current between the two poles of the supply current over the respective circuits for a shorter or longer period for each rotation of the driving shaft (for each phase and corresponding to the time during which a strip field remains in the reader). If, for instance, each phase is divided into fifteen equal parts (or any other number in excess of the 12 parts actually required in operations, to provide for flexibility), the framed (see Fig. 1, for instance) number of the figures designate the moment and the duration of the closing of the current and indicate the sign of the connected pole. Thus, for instance, the connection of a circuit, by the current dispatcher, to the + pole, from the seventh fifteenth of a phase till the sixth fifteenth of the next phase (i. e. the breaking of the circuit between the sixth and seventh fifteenth of every phase) has been conventionally indicated by the framed digits +7=6. This method of designation is employed to facilitate easy writing and of course has no arithmetical sense. If the current dispatcher connects a circuit to the negative pole between the sixth and eight fifteenth of every phase, this is indicated in front of the corresponding terminal, as -6=8 (framed) (see Fig. 1).

2. It also comprises the not illustrated but above mentioned group of relays and switches, for starting and stopping the installation (see the third paragraph before this one).

3. Still further, it comprises a reading apparatus 1 (Fig. 1) of this patent and according to my said United States Patent 1,863,097, through which apparatus the perforated strip the data of which are to be rearranged in predetermined order is passed. The electromagnet 2 (Fig. 1) releases the advance and the electromagnet 3 releases the return motion of the perforated strip. This back and forth movement of the strip can be accomplished by various methods as, for in-

stance, by a gear shift of conventional design, controlled automatically or by hand, applied to the strip advancing mechanism shown in Figure 12 of U. S. Patent 1,863,097 for the reading apparatus. By reversal of the switch 4 the electromagnets are made to change their function when the perforated strip is introduced into the reading apparatus by its right end instead of by the left end. The number 5 designates a set of four contacts for reading the perforations of the index lines while at 6 is shown the corresponding device for the line of the n3 (hundreds), at 7 the line of the n2 (tens), at 8 the line of the n1 (units), while at 9 is designated the device for the line for all the remaining sets of four contacts of the group field. The value of the individual points of the sets of four contacts is shown by the inserted number.

4. Said installation also includes a perforating apparatus 10 (Fig. 1) such as shown by Figures 7 to 11 inclusive in my said United States Patent 1,863,097, for perforating the new strip, the group fields of which have to be reproduced in predetermined order according to the data n3, n2, or n1. The electromagnets 11 and 12 as well as the switch 13 in this device have the same functions as have the devices 2, 3, and 4 in the reading apparatus 1. The groups of four electromagnets 14 to 18 for releasing the perforation of their corresponding lines correspond always to the sets of four contacts 5 to 9 of the reading apparatus.

5. In my installation there is provided what might be designated a strip movement control preferably comprising a group 19 (Fig. 1) of five relays of conventional design: Depending on the circumstances, relay 20 will operate the advance of the strip in the reading apparatus 1 while relay 27 occasions the return motion of the perforated strip. Relay 34 will also operate its advance but will cut out all operations which normally take place simultaneously when the strip is advanced. The relays 24 and 31 serve for determining the sequence in the excitation of the three first designated relays.

6. Still further, my invention comprises a group 39 of four relays (Fig. 1), which depend from the index contacts 5 (except for omissions indicated previously) and which operate on the transmission circuits of other parts or portions of the installation.

7. In my invention there are two selectors of four contacts each 50 and 54 (Fig. 1), and somewhat as suggested in Figures 5 and 6 of my prior United States Patent 1,863,097, with four relays, which, according to the position of the switch 58, (to the right of the reader) are energized by the data of the line 6 (n3), 7 (n2), or 8 (n1) of the reader and which in accordance with the momentary data of the line, connect the circuit sections 53 and 57 of the selectors 50 and 54 respectively with one of the circuit sections 59 and 60 of the distributor 61 (Fig. 2).

8. From the selector, which also acts as a decoder, the current goes to a distributor 61 (Fig. 2) which comprises a group of thirteen pairs of relays of conventional design which are adapted to transfer the perforations of a group field from the control strip onto a new or record strip if the data n of this field corresponds to the value for which the distributor is set at the moment.

9. An individual relay 72 (Fig. 1) is also provided depending upon the distributor 61 and assuring the operation of the first ones on the other devices.

10. Any individual relay 80 cooperates in the perforation of the new strip.

11. A switch 82, 83 is made use of at the end of the transmission.

5. The rearranging in predetermined order is effected by steps, the original perforated strip (in the reading apparatus 1) which is shown in Fig. 3 and schematically P0 in Fig. 4 being replaced by a new strip P1 (in the perforating apparatus), which is regrouped in numerical order according to n_3 or hundreds (Fig. 5), whereupon a new strip P2 (Fig. 6) regrouped in numerical order according to n_2 or tens is substituted (in the perforating apparatus) for the strip P1 (in the reading apparatus), which strip P2 is finally replaced by the last definitely and perfectly regrouped strip P3 (Fig. 7).

The operations in the first step are fundamentally as follows:

20. The original strip P0 (Fig. 3) passes through the reading apparatus 1 alternately in different directions. During the first passage the values of n_3 will permanently energize the corresponding relays 62 in the distributor 61 (Fig. 2) where- 25 by further and useless passages will be avoided in those cases where no values exist to be recorded; thereby economizing on time. This will be explained later.

The first passage or travel of the strip P0 through the reading apparatus 1 commences on the first group field with index 1, whereby the switches 58 assume the position shown at the right of Fig. 5. The perforation of the index closes the first contact 5 (Fig. 1) and the circuit $+1=10$ which is established by the cam of the current dispatcher from the 1/15 through the 10/15 of each phase of the cam shaft (Fig. 2), 5, 39, to the — pole of the current source, whereby the relay 39 becomes energized. By means of the circuit $+4=5$ (which is established in a manner as explained above in connection with $+1=10$), 30 69, 86 (Fig. 2), 86, relay coil 72, to the — pole (Fig. 1) the relay 72 will become energized and will remain so, due to its holding circuit $+3=2$, 35 relay contact 73, relay coil 72, to the — pole. Through the circuits $+5=6$, 43, 26, 33, 20 to the — pole, the coil 20 will be energized and will permanently remain so due to the circuits $+3=2$, 40 21, 20 to the — pole and $+1=12$, 48, 21, 20, to the — pole, since their interruptions in the cams of the current dispatcher do not coincide and since the coil 39 has arrived at its deenergized position and again closes the contact 48 prior to the interruption of the second holding circuit by the cam of the current dispatcher at the moment 12. The circuit $+6=7$, 49, 37, 76, 41, 14, 45, $-6=7$ to the — pole energizes the first coil 14 of the 45 perforating apparatus, thereby causing the perforation of the index 1 in the first group field of P1.

The coil 20 will thus remain energized during all the phases which correspond to all the group fields of the strip during the entire first travel of the strip P0 across the reading apparatus. The 50 energization of the coil 24 will be repeated in each phase by means of the circuit $+7=8$, 23, 24, to the — pole. The advance of strip P0 for the width of a field will also be repeated owing to the energization of the electromagnet 2 by means of the circuit $+6=7$, 22, 4, 2, to the — pole. When the subsequent group fields pass, the following performances will take place: In the same manner as before the coil 72 will in each phase, i. e. for each group field, be energized between the moments 4 of the momentary, and 2 of the

following phase, or $+4=2$. If, for instance, the data n_3 of a field is the value 1 expressed by the code perforations 3 and 4 of line 6, then the third and the fourth coil of the group 51 of selector 50 will become energized by means of the circuits $+1=10$, third and fourth contact of group line 6, 5 58, third and fourth coil of 51, to the — pole. This being so, the working circuit $+7=8$, 46, 79, 53, connection 8 of 59 (Figs. 1 and 2), the eighth relay 62 of the distributor 61, to the — pole, will be closed. Relay 62 will remain permanently energized because of its two holding circuits, the one $+7=6$, 63, which has been closed by the corresponding coil 62, the coil 62 itself, to the — pole, and the other $+1=10$, 68, 64, relay 62, to the — pole. The fact that the interruption of these two circuits in the current conveyor do not take place simultaneously explains this fact. After the first travel of strip P0, the relays 62 of the distributor 61 which correspond to the values n_3 contained on the strips, will be permanently energized.

When the end position of the strip in Fig. 4 has been reached the final field control strip of P0 with its index 1 comes into the reading apparatus, whereupon the following operations will take place:

The coil 39 (Fig. 1) will become energized, as previously, in such end position of the control strip. The circuit $+3=4$, 42, 88 (Figs. 1 and 2), 30 65 of the first relay 62 which is energized at this time, to the corresponding coil 66, to the — pole, thus energizes the relay 66. Owing to the energization of the first relay 62 the armature 65 will be disconnected from the lower contact, thus breaking the circuit and preventing the energization of all the other relays 66. The armature contact 68 of the energized relay 66 will interrupt the second holding circuit of the corresponding coil 62, ($+1=10$, 68, 64, relay 62, to the — pole) thereby cutting out such coil. Owing to the energization of the coil 66, the circuit of coil relay coil 72 through $+4=5$, 69, 86, 73 to the — pole, is interrupted in the group of contacts 69, so that said coil can no longer become energized. The circuit $+5=6$, 43, working contact 26 (relay 24 being energized), rest contact of 75, 21, to the — pole, energizes the coil 27, which in analogy to the coil 20, remains energized during the entire subsequent travel of strip P0 through the reading apparatus and will in each phase energize the coil 31 as well as the electromagnet 3, thereby moving the strip P0 backwards each time for the width of the field. The closing of the circuit $+6=7$, 77, 83, 85, electromagnet 3 of line 14, 45, $-6=7$, 55 to the — pole, releases in the first index field of the strip P1 the apparatus of the perforation of the index 3. The circuit $+6=7$, 77, 83, 85, 44, 13, 11, to the — pole will energize the electromagnet 11 and thereby designate the advance 60 and the substitution of the first field of P1. The index line also contains the perforations 1 and 3.

During the entire travel of the strip P0 the coil 72 carries no current and the perforations of those fields of strip P0 will be transferred 65 onto strip P1, which bear data n_3 corresponding to the value of the energized relay 66 (Fig. 2). In order to understand this fact, it is to be noted that the data n_3 of group 6 will in each phase be transferred to the coils 55. The working circuit $-6=8$, 51 of this selector 54 will be extended in accordance with the data n_3 , over one of the forked connections 60 (Figs. 1 and 2) and only that branch will become operative which leads from connection 60 over switches 71 over the 70 75

armature contact 10 of the energized relay 66 to point 87 (Figs. 1 and 2) and from there over contacts 47 and 78 and coil 80 to the + pole, thereby energizing the coil 80. This same circuit 5 will by its extension, and starting from contacts 78, pass all the coils 15, 16, 17, 18 and the contacts 6, 7, 8, 9, +1=10 and cause the energizing 10 of these electromagnets and the transfer from control strip P0 to record strip P1 of the perforations of the strip field. Only if the data n3 15 agree with the value of the energized relay 66 (Fig. 2) will the circuit +7=8, 81, 13, 11, to the 10 pole cause the advance of the new field perforated in the perforating apparatus 10 (Fig. 1).

15 After the second passage or travel the coil 72 (Fig. 1) will not become energized if the index 1 appears in the last field of P0. The coil 27 will become deenergized while the coil 20 will again become permanently energized, so that from this 20 moment the perforated strip P0 will be made to advance during its third travel. A closing of the circuit over +3=4, 42, 88 (Figs. 1 and 2) and 25 65 will permanently energize the next coil 66 corresponding to the energized coil 62, while the prior coil 66 will come to rest owing to the simultaneous interruption of its double auxiliary circuits +3=2, 67 (Fig. 2) and +1=12, 48, 89, (Figs. 1 and 2), 67. The index 3 will then be perforated in the strip P1, and said index field will be 30 replaced by the following one.

Reviewing the operation as outlined in the foregoing it may be stated that the process operates as follows:

During the first passage of the strip P0 through 35 the reading apparatus, the distributor 61 registers (by energizing the corresponding relay 62) the numbers n3 of the different existing hundreds, and does this by means of a selector 50. At the 40 end of the first passage, all the really existing numbers of n3, and these only, are registered by the distributor 61. Thereafter the to and fro travel of the strip P0 through the reading apparatus and between its limit positions follows, without intervention of the distributor 61, and 45 during which travel the fields of strip P0 are reproduced on strip P1 by the punching apparatus. This is done in such manner that the fields of the same number n3 are gathered and form a group, and so that the succession of said 50 groups corresponds to the increasing numbers of n3, i. e. are regrouped corresponding to n3.

This regrouped reproduction of the fields is produced in the following manner:

The second or reverse direction travel of the strip through the reader is controlled by the 55 relay 66 (now energized), corresponding to the smallest digit of the hundreds n3 met with during the first passage of strip P0 through the reader so that, during this passage, and through 60 the intervention of the selector 54, the fields bearing the digit corresponding to the energized relay 66 are alone reproduced on record strip P1 by the punching apparatus. When the number n3, of the field momentarily read in the reading 65 apparatus is the same number to which the particular and momentarily energized relay 66 corresponds (and there is only one relay 66 energized at a time, as previously explained), the common circuit, connecting all the magnets 15, 16, 17, 18 of the punching apparatus with the 70 pole (normally broken by the contacts 57 Fig. 1 and 70 Fig. 2) is closed on the terminal -6=8 (framed). As a consequence the field in question is reproduced on P1, in consequence of the connections between the sets of contacts 6, 7, 8, 9

and the corresponding sets of punching electromagnets 15, 16, 17, 18 Fig. 1.

At the end of the second passage of strip P0, through the reader, all the fields with the smallest digit n3 of the hundreds are reproduced in succession on the strip P1. 5

During the next passage of strip P0, that one of relays 66 corresponding to the next higher (and actually existing) digit n3 of the hundreds is energized. As has just been explained, only those fields whose n3 (hundreds) corresponds to the same digit as the momentarily energized relay 66, are reproduced on P1. During the following passages, the same operations are repeated for the different hundreds, until all the fields of strip P0 are reproduced in strip P1 (always fed in the same direction as the control strip) regrouped according to the hundreds. 10 15

In the intermediate position of the control strip P0 the coils 20 and 27 change their functions (Fig. 1) and the control of the transferred fields passes from one coil 66 to the next one. Furthermore, the individual series of hundreds which have been grouped on strip P1 according to n3 20 25 will automatically be separated by fields with the index 3.

After all the subsequently energized coils 66 (Fig. 2) have in this manner filled their functions and after the transfers of all the fields of control strip P0 onto record strip P1 have been 30 regrouped, the coil 72 will again be energized in one of its limit positions, so that the coil 20 again operates, and provides for the advance of the strip P0. The index 1 will now be perforated, the same as in the initial position, in the last field of record strip P1. In the course of the further advance of the strip P0, its final index 2 will be reached, whereupon, as already stated, the cutting out of the installation and the release of a signal will be effected. 35 40

If the cutting out of the last energized coil 66 (Fig. 2) takes place at a limit position such that a backward travel on the strip P0 in the reading apparatus has occurred, the energization of the coil 34 will follow the deenergization of coil 27, 45 since in this position the coil 34 is energized instead of coil 24 (Fig. 1). The coil 34 will now operate, the same as had the coil 20, and the forward advance of strip P0 (Fig. 1) takes place, whereby the opening of the armature contact 37 50 excludes any transmission. Therefore the strip P0 will, without any operation at all, reach its terminal position in which the above related performances take place.

In this stage of operation the strip P0 will be 55 replaced in the reading apparatus 1 by the record strip P1, while in the perforating apparatus 10 a new record strip P2 is substituted for the former strip P1.

In the transfer of the data from strip P1 onto 60 record strip P2 and in regrouping the fields connected with this transfer in accordance with the data n2 (tens) and within the field series already in accordance with the data n3 (hundreds), the operations are substantially the same as those 65 employed in the first transfer and sorting.

As will be seen from Fig. 6 the sole difference consists in the fact that the index 3 also takes the function of the initial and of the end index 1, so that the to and fro travel of the strip P1 70 takes place over the first series of hundreds, and thereafter each one of the next following series of hundreds. If, for instance, seven series of n3 appear, then the performances of the first transfer are automatically repeated seven times, each 75

time upon another section of the strip **P1**, now acting as a control strip, to be transferred.

Since the last entirely regrouped strip must begin on its left side with the smallest number and since the intermediate strips **P1** and **P2** are introduced in the left side of the reading apparatus, the switches **4**, **13**, **58**, **71** and **82**, **83** must take the positions shown in Figs. 5, 6, and 7 during the individual transmissions.

On the strip **P2** obtained in this manner, the fields which are regrouped according to **n3** (hundreds), are subdivided in series by an index field having the index **3**, which various series in turn, are divided in subdivision which are sorted according to **n2** (tens) and are separated by an index field with index **3**. The third and last transmission (Fig. 7) takes place exactly in the same manner, but successively for each one of these subsections. In the last step or stage, however, the switch **82**, **83** will be reversed, as shown at the right of Fig. 7, and therefore the perforation of the index **3** and the corresponding intermediate fields will be suppressed in the final strip **P3**, as has already been stated in the foregoing.

The regrouping of a strip, for instance by months, takes place in the same manner, as well as the sorting by any data whatever of a strip which has already been regrouped according to other data; in this latter case, the new regrouping takes place within the series already regrouped. It is to be noted that in the new strip which must be regrouped, the separating fields with the intermediary index **3** are missing between the series which are already regrouped according to the first data. The function of the separating signs is taken over by the comparing devices which will be described hereinafter and which whenever new data appear, that is to say when the end of a series is reached and a new series has begun, will terminate the desired performances in consequence of the change of the first datum taking place in these positions.

From the description of the reading and perforating apparatus, as contained in my said Patent 1,863,097, the counters, the repeaters, and the printing apparatus, the latter contained in my said Patent 1,863,098, it will be seen that an installation comprising these apparatuses and provided with a couple of the above mentioned selectors and the usual relays, will after the performance of the required reversals and after the necessary circuit connections have been established, permit each data group to automatically repeat a series composed at will of simultaneous operations. It is further seen, that for any choice of these operations, a predetermined number of automatic repetitions, which depend solely on particular data appearing in the course of the working operation, can take place, and further, that it is possible to cancel these operations partially automatically, or either to replace them, by others, complete them, or change their sequence during the performance of the operations, in accordance with particular data which occur. The individual operations of such series comprise, among others, the advance of the perforated strip in either direction, the advance of the printing sheet for a smaller or a greater line distance, the regular entry or transfer of data or of a result, the selection of such entries or transfers, the return to zero of a counter, etc. These operations may comprise at will additions and subtractions, with the help of a repeater, which may also comprise multiplications and involution. Provision may be made for permitting any pre-

determined data or different data which occur simultaneously to have an influence both on each other and on the performance of the operations.

In the course of statistical work it becomes necessary at times either to perform or to suspend operations in accordance with the relative value of two data which may appear either simultaneously or at different times, and not in accordance with occurrence or non-occurrence of specific data, or their absolute value.

It occurs, for instance, that certain operations are to take place or are to be suppressed according to whether datum **a** is greater, is equal to, or is smaller than the simultaneously occurring data **b**, as the case may be, or than the data **b** of the immediately preceding phase. The grouping of relays (Fig. 8), which is called a "comparing device", serves for the determination and for the comparison of such relations between the data.

Let it be assumed that **ab**, **a'b'**, **a''b''** (Fig. 8) designate the one set of data, and **cd**, **c'd'**, **c''d''** designate the other data in the fields which follow one another, and that each of the two data requires, for instance, two lines of four contacts. In this case the distributor will consist of two groups **110** and **111**, each group comprising a group of coils **445**, **449** and **455**; **345**, **349** and **355**; **245**, **249** and **255**; **145**, **149** and **155** shown in Fig. 8. Every group of three relays arranged one on top of the other and consisting of one relay of each of the three groups **445**, **449** and **455**; **345**, **349** and **355**, etc., constitutes a comparer "element", the value of which is indicated by the encircled number **1** to **4**. It is to be remembered, that the datum **1** for instance, is obtained according to code by the perforation of the elements corresponding to the encircled points **3** and **4** and is effected by the energization of the corresponding relays of the group **110**, should the datum be an **n2** value. The framed numbers of Fig. 8 depict the moment and the duration (expressed in fifteenths of a phase) of closings of the circuit which will be caused in the corresponding circuits through the intermediary of a current dispatcher of conventional design and previously explained for Figures 1 and 2.

Data occurring simultaneously in the same field of the strip or on the field of different strips are to be compared.

The datum **a'b'** appearing in the reader, which is explained in my patent 1,863,097 and schematically shown in the upper left hand corner of Fig. 1 causes the energization of the upper coils **445**, **345**, **245** and **145** of group **110** and **445'**, **345'**, **245'** and **145'** of group **111** through the circuit positive pole, **1=2**, the reader contacts (6 of Fig. 1 for **a'** and **7** for **b'** for instance) the four line circuit **112** or **112'** to the upper coils, to the negative pole. The coils corresponding to the performances under the reader are energized. The energization will be prolonged until the moment **12** by means of the auxiliary circuit of the terminals **116** and **116'**. In the same manner the datum **c'd'** causes the energization of the corresponding intermediate coils **449**, **349**, etc., of the groups **110** and **111**. If in the element **4** of group **110** (that is to say the highest number position) the coil **445** is energized but the coil **449** is at rest then it is evident that the datum **a'b'** is greater than **c'd'** and the working current of terminal **118** passes over **447** upper contact, **452** lower contact, **131** and **131'** directly without passage through any of the subsequent groups of **110** and **111**, of the comparer.

If coil 445 is at rest while coil 449 is energized it is evident that the datum $a'b'$ set up in group 445, 345, etc. is smaller than datum $c'd'$, set up in group 449, 349, etc., and the working current this time passes from terminal 118 over lower contact 447, upper contact 451, 129 and 129', also without passing through the subsequent groups of 110 and 111. If finally the coils 445 and 449 are either both energized or both at rest, there exists equality in this code element and the result depends upon the following elements of the group. If both are energized, for instance, the working current passes from terminal 118 over upper contact 447, upper contact 452 to contact 347 where the process is repeated in the same manner. Equality of all elements exists if $a'b' = c'd'$, in which the working current passes from terminal 118 through all the elements of 110, 124, 118, through the elements of 111 and finally through terminal 124'.

If, for example, $a' = 7$, $b' = 4$, $c' = 7$ and $d' = 2$ the data to be compared are 74 and 72. The current passing through the reader will energize the coils 445 and 345 in group 110 for the value 7, and the coil 445' for the value 4. In the same manner 72 in the reader will energize coils 449 and 349 in group 110 and 249' in group 111. The working current follows the following circuit: Terminal 118, upper contact 447, upper contact 452, upper contact 347 and 352, lower contacts 247, 251, 147 and 151, 124, 118', upper contact 447', lower contact 452' and terminal 131' which indicates that $a'b'$ is larger than $c'd'$.

If now, datum $a'b'$ is to be compared with the other datum cd which had appeared in the preceding phase, the first datum will as in the previous case, be transmitted into relays 445, 345, etc. During the preceding phase the datum cd has been transmitted to relays 449, 349, etc. and at the end of said phase, was transmitted from the relays 449, 349, etc. by the closing of the circuit of terminal 125 to the lower group of relays 455, 355, etc. This circuit passes from terminal 125 under all the relays 449, 349, etc. and energizes the relays 455, 355, etc. corresponding to the energized relays of the middle line 449, 349, etc. If 449, for instance, is energized the current passes from terminal 125 over 453, relay 455, to the negative pole. The relay 455 remains energized during the rest of the preceding and the present phase through its auxiliary circuit 11=10, 133, 456, 455, to the negative pole. In the momentary or present phase the datum of relays 445, 345, etc. will be compared with that of the relays 455, 355, etc. in the same manner as previously described, but making use of the working current of terminal 120, from where the current passes for the example comparison of 74 and 72 over upper contacts 448, 460, 348 and 360, lower contacts 248, 259, 148 and 159, 136, 120, upper contact 448', lower contact 460' and terminal 143'.

If, finally, the momentary datum $c'd'$ is to be compared with the datum cd of the same data group but in the preceding phase, the relays 449, 349, etc. of the middle line and the relays 455, 355, etc. of the lower line and the working current over terminal 127 will be used, the other relays remaining the same as in the preceding case.

If a group of relays 445, 345, etc. and 449, 349, etc. of Fig. 8 is provided with a plurality of armature contacts 447, 451, 452, 347, 351, 352, etc. It will constitute a "multiple comparison device" with the help of which divisions etc. may be executed in the shortest possible time.

The reproduction in predetermined order is made speedier and, in fact, for the first time practical, by limiting the back and forth movement of the first (P1) and second (P2) reproduction strips (Figs. 5 and 6) to the space between indices 3, perforated into a special field, until this part of the strip is completely regrouped. For example, on strip P1 the strip travels back and forth only over the part carrying the same hundred designation (Figs. 5, $n3=0$, or $n3=2$, etc.) until the selection by the ten designation $n2$ and its reproduction on P2 (Fig. 6) in that order is completed.

The effect of indices 3 can be attained by the use of the comparer, described above. In that case the digit $n3$, to which the strip P1 passing through the reader 1 (Fig. 1) was previously grouped, is transmitted in code by means of a four-wire lead, connected to the four wires which lead from the switches 58 to the right (not shown), to the four-pole jacks 112 and 122 (Fig. 8). The current entering terminal 112 energizes the relays 445, 345, 245, 145, and the current entering through terminal 122 energizes relays 449, 349, 249, 149 in accordance with the classification digit perforation in the reader at the moment. The current +11=12 will, towards the end of the phase energize the relays 455, 355, 255 and 155 corresponding to the energized relays 449, 349, 249 and 149, and the holding circuit +11=10 will keep them energized for the succeeding phase. In this succeeding phase the next field will enter the reader and its index perforation will energize the first two sets of relays (445, 345, etc. and 449, 349, etc.) according to its classification digit. The comparison of the relay group 445, 345, 245 and 145 and the groups 455, 355, 255, and 155 now takes place through the second circuit +2=3 from the top, in the manner explained previously. As long as the two succeeding classification digits are equal in value, the strip movement will be allowed to continue in the same direction and the perforation is taking place. A difference in the value of the two succeeding classification digits will cause the strip movement to reverse its direction and will prevent perforating temporarily. This is accomplished by connecting the two exit terminals 141 and 143 (Fig. 8) to the lead from point 1 (Fig. 1) of line 5 of reader 1, thus energizing relay 39 which will cause the reversal of the direction of the strip movement and prevent perforation in lines 15, 16, 17 and 18, in the manner described previously (last paragraph page 15 and page 16). This connection between the regrouping apparatus and the comparer was not illustrated, as it is only a question of connecting the six wires. In this manner the comparer takes over the function of the special index perforations.

It is of course obvious that once the broad features of my invention are disclosed, numerous modifications and adaptations thereof will readily occur to those skilled in the art. Accordingly, it is contemplated that the invention be limited only by the scope of the appended claims.

What I claim is:

1. In a combined regrouping and reproducing mechanism, where data in a strip comprised of fields is passed under a reading means and is selected according to particular classification digits arranged one on each field and then reproduced, a distributor for determining the order of reproduction, the said distributor comprising a plurality of relays adapted to be energized according to the value of the said classification

digits of the several fields, the energized relays being retained over a period of time in their energized position, said group of distributors also comprising a second group of relays each relay of which corresponds to a relay of the first group, that relay of the second group corresponding to the first energized relay of the first group being energized upon repassage of the strip through the reading means, whereby when the digit corresponding to the energized relay of the second group appears in the reading means, a working circuit is closed by the said relay of the second group and causes the direct reproduction of at least part of the data of the field under the reading means.

2. In a combined regrouping and reproducing mechanism, where data in a strip comprised of fields is passed under a reading means and is selected according to particular classification digits arranged one on each field and then reproduced, a distributor for determining the order of reproduction, the said distributor comprising a plurality of relays adapted to be energized according to the value of the said classification digits of the several fields, the energized relays being retained over a period of time in their energized position, a second group of relays each relay of which corresponds to a relay of the first group, that relay of the second group corresponding to the first energized relay of the first group being energized upon repassage of the strip through the reading means, whereby when the digit corresponding to the energized relay of the second group appears in the reading means, a working circuit is closed by the said relay of the second group and causes the direct reproduction of at least part of the data of the field under the reading means, energization of a relay of the second group causing the deenergization of the corresponding relay of the first group.

3. A combined regrouping and reproducing mechanism for reading data from strips comprised of a series of perforated fields, each having classification digits thereon, comprising means for reading the perforations, selecting means connected with and controlled by said reading means for selecting certain classes of data from the record, means under the control of both the said reading means and said selecting means for reproducing in fields at least part of the selected classes of data on a second strip, and means under the control of both said reading means and said selecting means for inserting on the second strip an index mark on a special field at the end of each group of fields comprising the same classification digit according to which the regrouping has been carried out, which index mark denotes the end of the movement of the strip in one direction.

4. A combined regrouping and reproducing mechanism for reading data from strips comprised of a series of perforated fields, each having classification digits thereon, comprising means for reading the perforations, selecting means connected with and controlled by said reading means for selecting certain classes of

data from the record, means under the control of both the said reading means and said selecting means for reproducing in fields at least part of the selected classes of data on a second strip, means under the control of both said reading means and said selecting means for inserting on the second strip an index mark on a special field at the end of each group of fields comprising the same classification digit according to which the regrouping has been carried out, which index mark denotes the end of the movement of the strip in one direction, and means operable at will for deenergizing said index-inserting means, to discontinue provision of index marks on the record strips.

5. A combined regrouping and reproducing mechanism for reading data from strips comprised of a series of perforated fields, each having classification digits thereon, comprising means for reading the perforations, selecting means connected with and controlled by said reading means for selecting certain classes of data from the record, means under the control of both the said reading means and the said selecting means for reproducing in fields at least part of the selected classes of data on a second strip, means for comparing classification digits on two succeeding strip fields, and means, depending from said comparing means, which will cause the reversing of the direction of the strip movement in the reader and the temporary suspension of any perforation in the event that the classification digits of two succeeding strip fields and not of equal value.

6. A combined sorting and reproducing mechanism, comprising means for receiving and reading perforated records containing data in code thereon, a distributor for controlling and causing the automatic reproduction in predetermined order in accordance with the arbitrarily selected classification digit of at least part of the perforated record in the reading means, and means controlled by the said distributor for reproducing directly the data in the reading means.

7. A combined sorting and reproducing mechanism, comprising means for reading the fields of a perforated strip containing data thereon in code, part of said data being arbitrarily selected as classification data, the succeeding fields of the said strip being out of order in regard to the classification data, feeding means for causing the displacement of the strip field by field in either direction, means for receiving and perforating a copy strip, connecting means between the reading means and the perforating means, perforating means for causing the reproduction on a field of the copy strip of at least part of the data in the field under the reading means, and a distributor for controlling the feeding means and for causing the automatic regrouping and reproduction on the copy strip in predetermined order in accordance with the classification data of at least part of the data on the strip field under the reading means.

CHARLES BOREL. 65
